Victor J. Evans

ATTORNEY

UNITED STATES PATENT OFFICE.

WILBERT P. MOORE, OF WORLAND, WYOMING.

SPARK-PLUG TESTER.

Application filed March 27, 1922. Serial No. 547,044.

To all whom it may concern:

Be it known that I, WILBERT P. MOORE, a citizen of the United States, residing at Worland, in the county of Washakie and 5 State of Wyoming, have invented new and useful Improvements in Spark-Plug Testers, of which the following is a specification.

This invention relates to a device for testing the ignition circuit of an internal combustion motor, the principal object of the invention being to provide means on the spark plugs for short circuiting the same to tell whether or not the electric system is in 10 proper condition.

Another object of the invention is to attach the device to the plug in such a manner that it can be moved into operative and inoperative position as required.

20 This invention also consists in certain other features of construction and in the combination and arrangement of the several parts, to be hereinafter fully described, illustrated in the accompanying drawings 25 and specifically pointed out in the appended claim.

In describing my invention in detail, reference will be had to the accompanying drawings wherein like characters denote like 30 or corresponding parts throughout the several views, and in which:—

Figure 1 is a plan view of a plug constructed in accordance with my invention.

Figures 2 and 3 are detail views.

35 In these views 1 indicates a spark plug which may be made of any desired type and

2 indicates my device which is preferably of U-shape and formed of spring metal, the legs engaging opposite sides of the shell of the plug and being pivotally secured thereto by means of the pivot points 3 on the legs 40 engaging recesses 4 on the plug.

This arrangement of parts will permit the device to extend at right angles from the plug, when it will be in inoperative position, or to permit it to be swung towards the outer end of the plug so as to come adjacent the electrode of the plug to short circuit the same, thus giving a spark if the circuit is 45 closed. If a spark does not occur this will 50 be proof that something is wrong with the electric system.

By this invention it will be seen that the system can be easily and quickly tested without removing the plugs or applying tools 55 thereto.

It is thought from the foregoing description that the advantages and novel features of my invention will be readily apparent.

I desire it to be understood that I may 60 make changes in the construction and in the combination and arrangement of the several parts, provided that such changes fall within the scope of the appended claim.

What I claim is:—

A device of the class described comprising a strip of spring metal bent into U-shape and having pivot points punched in its legs for engaging recesses in the shell of a spark plug.

In testimony whereof I affix my signature.

WILBERT P. MOORE.
